R. O. JACKSON.
ELECTRODE HOLDER.
APPLICATION FILED FEB. 23, 1917.

1,242,554.

Patented Oct. 9, 1917.

Inventor,
Raymond O. Jackson.
By Bakewell & Howlett, Inc.

UNITED STATES PATENT OFFICE.

RAYMOND O. JACKSON, OF ST. LOUIS, MISSOURI, ASSIGNOR, BY MESNE ASSIGNMENTS, TO METALLURGICAL LABORATORIES, INCORPORATED, OF CHICAGO, ILLINOIS, A CORPORATION OF ILLINOIS.

ELECTRODE-HOLDER.

1,242,554.

Specification of Letters Patent.

Patented Oct. 9, 1917.

Application filed February 23, 1917. Serial No. 150,555.

To all whom it may concern:

Be it known that I, RAYMOND O. JACKSON, a citizen of the United States, residing at St. Louis, Missouri, have invented a certain new and useful Improvement in Electrode-Holders, of which the following is a full, clear, and exact description, such as will enable others skilled in the art to which it appertains to make and use the same.

10 This invention relates to devices of the kind commonly termed electrode holders, which are used for establishing electrical connection between a supply conductor and an electrode that becomes highly heated when 15 it is in use, such, for example, as the electrode of an electric furnace.

One object of my invention is to provide an electrode holder of novel construction that will effectively cool the electrode with 20 which it is used.

Another object is to provide an inexpensive water-cooled electrode holder that can be clamped tightly to the electrode with which it is used, and which is so constructed 25 that it can be easily connected to a supply conductor. Other objects and desirable features of my invention will be herein-after pointed out.

Figure 1 of the drawings is a vertical sectional view, illustrating an electrode holder constructed in accordance with my invention, used for connecting a supply conductor to the electrode of an electric furnace.

Fig. 2 is a top plan view of said electrode holder.

Fig. 3 is a vertical sectional view, taken on the line 3—3 of Fig. 1.

Fig. 4 is a side elevational view, illustrating another form of my invention; and

40 Fig. 5 is a perspective view of my improved electrode holder with the coil removed.

Referring to Fig. 1 of the drawings, which illustrates the preferred form of my invention, A designates an electrode that projects outwardly through the wall 1 of an electric furnace, and B designates a supply conductor. My improved electrode holder, which is used for establishing electrical connection between said supply conductor and said electrode, comprises a body portion that is adapted to be mounted on the outer end portion of the electrode A, a cooling element in said body portion that completely sur-

rounds the electrode and through which wa- 55 ter or any other suitable cooling medium can circulate, and means for connecting the supply conductor B to said body portion. The body portion of the holder is preferably formed in such a manner that it can be 60 clamped in snug engagement with the electrode, so as to insure a good electrical contact between the electrode and the holder, and in the embodiment of my invention herein 65 illustrated the body portion of the holder consists of a split clamp formed from two plates 2 and 3 of copper or other suitable material arranged one within the other and spaced apart, so as to receive the cooling 70 element of the holder, which preferably consists of a coil of pipe C whose opposite ends are adapted to be connected to pipes 4, as shown in Fig. 2, through which water circulates. The plate 2 that forms the outer wall 75 of the body portion of the holder is provided with a pair of ears or flanges 2^a that extend parallel to a pair of ears or flanges 3^a on the inner plate 3, and bolts or other suitable fastening devices 5 are arranged transversely in said ears, as shown in Fig. 3, so 80 as to enable the inner plate 3 to be drawn into snug engagement with the electrode A by tightening the nuts on the bolts 5. Spacing devices or fillers 6 are arranged between the ears 2^a on the outer plate and the 85 ears 3^a on the inner plate of the holder, so as to impart sufficient rigidity to same to prevent them from being bent out of shape when the nuts on the bolts 5 are tightened, the spacers 6 preferably extending into the 90 space in the body portion of the holder that receives the coil C, so as to reinforce and strengthen the lugs 3^a on the inner plate at the point where they merge into said plate. The inner plate 3 is provided with holes 7, 95 as indicated in Fig. 3, through which the helixes of the coil C pass, and the inner edges of the spacers 6 are notched at 8, as shown in Fig. 1, so as to provide a clearance for the helixes of the water coil. The 100 end portions of the coil C project outwardly from the body of the holder through notches 9 formed in the plate 2, and said plate 2 is provided with lugs 10 that lap over the projecting end portions of the coil 105 C, so as to eliminate the possibility of the upper side of the coil moving longitudinally with respect to the body portion of the

holder. The lower side of the coil is securely held in position in the body portion of the holder, and the helixes of the coil are held in proper spaced relation by the portions of the inner plate 3 that lie between the openings 8 in said plate through which the helixes of the coil pass. Various means may be used for connecting the supply conductor B to the body portion of the holder, but I prefer to provide one of the spacers or fillers 6 with a portion to which the supply conductor can be connected. In the form of my invention shown in Fig. 1 one of the spacers 6 is provided with a flat, plate-like extension 6^a to which a braided supply conductor can be connected by means of clamping plates 11 through which bolts or other suitable fastening devices 12 pass, as shown in Figs. 1 and 2. In the form of my invention shown in Fig. 4, one of the spacers 6 is provided with an extension 6^b of tubular form that is adapted to receive a conductor B' of circular shape in cross section that is retained in position by set screws 13.

25 An electrode holder of the construction above described is particularly adapted for use with an electric furnace of the type in which the electrodes are used to conduct the heat out of the chamber of the furnace, owing to the fact that the cooling element C of the holder completely surrounds the portion of the electrode that projects outwardly through the wall of the furnace, and thus cools same so effectively that there is no liability of the electrode becoming heated to such a high degree that it will oxidize. The cooling element of the holder is of such form that it does not interfere with the expansion or contraction of the body portion 40 of the holder, thus enabling the holder to be clamped tightly to the electrode and insuring a good electrical contact between said parts. Still another desirable feature of such an electrode holder is that there are no joints in the cooling element to be kept water tight, thus eliminating trouble in keeping the holder in operative condition and also enabling the holder to be manufactured cheaply.

45 Having thus described my invention, what I claim, and desire to secure by Letters Patent, is:

1. An electrode holder, comprising a body portion constructed to receive an electrode, a cooling element in said body portion that completely surrounds the electrode, and means for enabling said body portion to be clamped in snug engagement with the electrode.

60 2. An electrode holder, comprising a body

portion constructed to receive an electrode, and a cooling element in said body portion consisting of a coil through which a cooling medium circulates.

3. A device for the purpose described, 65 comprising a coil through which a cooling medium can circulate, and means for securing said coil to an electrode and establishing electrical connection between the electrode and a supply of electrical energy. 70

4. An electrode holder, comprising a split body portion that is adapted to receive an electrode, and a cooling coil arranged on said body portion in such a manner that it does not interfere with the expansion or contraction of said body portion. 75

5. An electrode holder, comprising a body portion provided with a double wall, and a cooling coil arranged in the space between the walls of said body portion. 80

6. An electrode holder, comprising a body portion provided with a double wall, a cooling coil arranged in the space between the walls of said body portion, said body portion being split or divided, and means for clamping said body portion to an electrode. 85

7. An electrode holder, comprising a body portion that is adapted to receive an electrode, means combined with said body portion to which a supply conductor can be connected, and a coil on said body portion through which a cooling medium can circulate. 90

8. An electrode holder, comprising a tubular-shaped body portion that is split or longitudinally divided at one point, ears or lugs on said body portion that are adapted to receive fastening devices which clamp said body portion to the electrode with which the holder is used, and a cooling coil on said body portion that extends across the split or joint in said body portion. 95

9. An electrode holder, comprising a body portion in the form of a split clamp that has two spaced walls of substantially tubular form arranged one within the other, and a cooling coil in the space between said walls whose helixes pass through openings in said inner wall and extend across the split or joint in the clamp. 100

10. An electrode holder, comprising a double walled body portion of substantially tubular form that is split or longitudinally divided at one point, means for contracting said body portion, an extension on said body portion to which a supply conductor can be connected, and a coil arranged between the walls of said body portion through which a cooling medium can circulate. 115

RAYMOND O. JACKSON.
